NURSING BOTTLE

Eugene R. Luedtke, Reedsburg, Wis., assignor to HanksCraft Company, Reedsburg, Wis., a corporation of Wisconsin

Filed July 20, 1960, Ser. No. 61,449

Term of patent 14 years

(Cl. D83—8)

FIG. 2

FIG. 1

FIG. 4

FIG. 5

FIG. 6

FIG. 7

FIG. 3

FIG. 8

FIG. 1 is a front elevational view of a nursing bottle embodying my new design;

FIG. 2 is a top plan view thereof;

FIG. 3 is a bottom plan view thereof;

FIG. 4 is a rear elevational view thereof;

FIG. 5 is a side elevational view thereof taken from the right of FIG. 1;

FIG. 6 is a cross-sectional view thereof taken substantially along line 6—6 in FIG. 1;

FIG. 7 is a cross-sectional view thereof taken substantially along line 7—7 in FIG. 1; and

FIG. 8 is a cross-sectional view thereof taken substantially along line 8—8 in FIG. 1.

I claim:

The ornamental design for a nursing bottle, substantially as shown.
